US00D666653S

(12) **United States Design Patent**
Nusser

(10) **Patent No.:** **US D666,653 S**
(45) **Date of Patent:** **** Sep. 4, 2012**

(54) **MICROSCOPE ASSEMBLY**

(75) Inventor: **Daniel Nusser**, Aalen (DE)

(73) Assignee: **Carl Zeiss Meditec AG**, Jena (DE)

(**) Term: **14 Years**

(21) Appl. No.: **29/404,920**

(22) Filed: **Oct. 26, 2011**

Related U.S. Application Data

(62) Division of application No. 29/347,837, filed on Jun. 21, 2010, now Pat. No. Des. 650,405.

(30) **Foreign Application Priority Data**

Dec. 22, 2009 (EM) 001186019

(57) **CLAIM**

The ornamental design for a microscope assembly, as shown and described.

DESCRIPTION

FIG. 1 is a perspective view of the microscope assembly of my new design;

FIG. 2 is a bottom plan view of said microscope assembly of FIG. 1;

FIG. 3 is a rear elevation view of said microscope assembly of FIG. 1;

FIG. 4 is a left side elevation view of said microscope assembly of FIG. 1;

FIG. 5 is a front elevation view of said microscope assembly of FIG. 1;

FIG. 6 is a right side elevation view of said microscope assembly of FIG. 1; and,

FIG. 7 is a top plan view of said microscope assembly of FIG. 1.

The broken lines form no part of the claimed design.

1 Claim, 7 Drawing Sheets
